UNITED STATES PATENT OFFICE.

AXEL KAP, OF EAGLE BEND, MINNESOTA.

PLOW.

SPECIFICATION forming part of Letters Patent No. 698,023, dated April 22, 1902.

Application filed October 30, 1901. Serial No. 80,552. (No model.)

To all whom it may concern:

Be it known that I, AXEL KAP, of Eagle Bend, county of Todd, and State of Minnesota, have invented certain new and useful 5 Improvements in Plows; and I do hereby declare the following is a full and clear description.

My invention relates to plows.

The objects of my invention are to provide 10 a gang-plow with means whereby each plow may have a rising movement independent of the other or others for the purpose of passing over and avoiding obstructions, such as stones and the like. I prefer to provide the 15 gang-plow with wheels and in connection therewith the mechanism for lifting the plows out of the ground upon the wheels when the plows are not being used, as in driving to and from the field or in turning around or the 20 like.

With these objects in view my invention consists in the following construction and combination of parts, the details of which will first be fully set forth and described, and the 25 novel features thereafter pointed out and claimed.

Figure 1 represents a perspective view of a gang-plow to which I have applied my improvements. Fig. 2 represents a side elevation 30 of the same, and Fig. 3 represents a similar view showing the plow-beams raised.

1 is an axle carrying a set of wheels 2.

3 represents a rectangular vertical frame carrying two sets of vertical standards 4, all 35 four of which are secured to the axle 1. The inner wheel 2 is journaled between these sets of standards and the plow-beams, which latter are carried between the pairs of standards on each side of the wheel.

40 5 is a shaft rigid with the frame 3, to which the front ends or clevises of the plow-beams are secured. Brace-bars 6 projecting forwardly from the standards 4 serve to maintain the position of the shaft 5. The standards 4 serve as guides for the plow-beams 7. The draft tongue or pole 8 is carried by a 45 frame 9, secured to the shaft 5.

10 and 11 are braces connecting the outer end of the axle 1 with the frame 3 and the 50 frame 9.

The frame is provided with a cross-piece 12, and upon this cross-piece is pivoted a lever

13, the front end of which is provided with a vertical link-bar 14, connected with the shaft to which the plows are attached. The rear 55 end of the lever 13 is provided with a handle 15, carrying a locking device by means of which the lever may be raised and lowered for the purpose of raising and lowering the plow-beams. For this purpose one of the plow-beams 7 is provided with a segmental notched 60 upwardly-projecting bar 16, by means of which the lever may be locked at any suitable degree of inclination. When the lever is depressed, so that the lock drops into the notch 65 17, the inner plow-beam is raised sufficiently high to take that plow out of the ground, and through its connection with the gang-plow coupling 18 the other plow is also lifted clear 70 of the soil.

The gang-plow coupling 18 comprises a rigid frame attachment 19, securely fastened to the inner plow-beam 7. It is provided with an upwardly-extending frame portion 20, carrying a laterally-projecting vertical 75 bearing 21. The outer plow-beam 7 is provided with a rigid coupling 22, having a laterally-projecting vertical shaft 23, which passes through and has a vertical play within the projecting bearing 21 upon the other plow. 80 It will be seen that each plow has an independently rising-and-falling motion with respect to the other plow upon the vertical bearings 21 and 23, which permits either plow upon striking a stone or other obstruction to 85 ride over the same without affecting the other plow or taking it from the soil. When the lever 13 is depressed for the purpose of taking the plow out of the ground, the inner plow first rises until its bearing 21 reaches 90 the upper limit of the bearing 23 of the outer plow, and upon further depressing the lever 13 the outer plow will also be raised clear of the ground.

It will be noticed in my construction that 95 the plows are perfectly guided by the frame 3 and that the inner wheel of the plow runs upon and parallel with the plow-beams and also within the frame 3. The result of this construction is a very compact plow in which 100 all the wheels of the plow run upon the stubble or land side at all times except when finishing a field. This is a very important arrangement for the reason that none of the

wheels are in the furrow or plowed ground, where the traction is greater and requires more draft from the team.

It will be understood that while I have shown exemplifying means for carrying out the spirit of my invention yet my invention is not limited to the specific construction set forth and described. On the contrary, my invention contemplates all departures or changes from the specific construction herein set forth which are within the scope of my claims.

Having described my invention, what I claim as new, and desire to secure by Letters 15 Patent, is—

1. In a plow, the combination of wheels, an axle, a frame carried by the axle, one of the wheels mounted within the frame, plows mounted upon both sides of the wheel within 20 the frame, a gang-coupling located in rear of the axle connecting the plow-gangs to permit independent vertical movement thereof and a lock-lever for elevating the plows.
2. In a plow, the combination of plow-

beams, a frame, an axle and wheels mounted 25 in the frame, whereby the inner wheel runs between the plow-beams, and a gang-coupling for the plow-beams located in rear of the axle permitting independent vertical movement of each of the plows.

3. In a wheel-plow, the combination of two plows, a coupling directly connecting the two beams of the plow-gangs, said coupling comprising vertical bearings which permit the independent rise and fall of each plow-beam. 30

4. A gang-plow coupling comprising two members, each provided with clips for securing the plow-beam thereto and each provided with inner projecting members having vertical sliding bearings, whereby one member of 40 the coupling may have a vertical movement with respect to the other.

In testimony whereof I have affixed my signature in the presence of two witnesses.

AXEL KAP.
